DISPLAY STAND

Roy L. Flannery, Chicago, Ill., assignor to The Boye
Needle Company, Chicago, Ill., a corporation of Illinois

Application March 1, 1955, Serial No. 34,794

Term of patent 14 years

(Cl. D80—9)

Fig. 1 is a top plan view of a display stand showing my new design,

Fig. 2 is a side elevational view, and

Fig. 3 is a side elevational view taken near a corner of the triangular frame.

I claim:

The ornamental design for a display stand, as shown.
